UNITED STATES PATENT OFFICE.

ELLICOTT McCONNELL, OF BROOKLYN, NEW YORK.

MECHANICAL STOKER.

SPECIFICATION forming part of Letters Patent No. 711,669, dated October 21, 1902.

Application filed June 3, 1902. Serial No. 110,025. (No model.)

To all whom it may concern:

Be it known that I, ELLICOTT McCONNELL, a citizen of the United States, residing in the borough of Brooklyn, city of New York, county 5 of Kings, and State of New York, have invented a new and useful Improvement in Mechanical Stokers, of which the following is a full, clear, and exact description, reference being had to the accompanying drawings, which form a 10 part of this specification.

My invention relates to mechanical stokers. It is particularly adapted to application to the fire-box of a locomotive, although it is applicable with equal advantage to a station- 15 ary boiler.

One of the difficulties incidental to mechanical stoking is to secure an even and uniform distribution of the fuel over the grate-surface.

20 The object of my invention is to effect an even distribution of coal over the entire grate-surface. This I accomplish by such a construction and arrangement of an underfeed stoker that the coal will be uniformly distributed along the longitudinal center line of the 25 grate and thence spread out over the grate and toward the sides thereof in a layer of substantially uniform thickness.

20 The invention consists of the combination, with the grate, of a reciprocating fuel retort, conveyer, or trough arranged below the longitudinal center thereof combined with stationary distributing-deflectors that are preferably capable of swinging on a pivot.

35 The invention also consists of the above arrangement combined with a plate moving with the trough, which is adapted to slide under the mouth of the hopper and alternately cover and uncover the same in the reciprocating movement of the trough.

30 The invention also consists in a special arrangement of the deflectors as to location and relative size, in a special construction of said deflectors, and in details of construction and 45 arrangement.

In the drawings, Figure 1 is a side elevation of a locomotive with my invention applied. Fig. 2 is longitudinal section, showing in detail the bottom of the fire-box, stoker, and 50 hopper. Fig. 3 is a plan view of Fig. 2. Fig. 4 is a section on line 4 4 of Fig. 2. Figs. 5, 6, and 7 are sections on line 5 5 of Fig. 4,

showing the different positions assumed by one of the pivoted deflectors at different positions of the stoker.

55

A is the fire-box of a locomotive; X, the boiler. The grate of the fire-box is composed of two sets of grate-bars B B, said grate-bars being shown as extending transversely and the two sets extending longitudinally of the 60 fire-box and separated by an open space. The inner end of each transversely-extending grate-bar rests in a bearing in one of the longitudinally-extending bearing-bars Y Y, while the other end rests in a bearing in one 65 of the longitudinally-extending bars Z Z. These bearing-bars are each secured to the mud-ring M of the fire-box by means of bolts m.

Secured to the bearing-bars Y Y are a plurality of brackets y, which extend below the 70 bearing-bars. c represents rollers rotatable in bearings in the lower ends of oppositely-located brackets y.

C is a trough or conveyer, of steel, cast-iron, or other suitable material, of greater 75 length than the length of the fire-box or the longitudinal dimensions of the grate-surface, said trough resting on the rollers c. The bearing-bars Y Y are provided with recesses extending throughout their entire length of 80 a depth substantially equal to the thickness of the side members of the trough, and the trough fits within said recesses, as shown in Fig. 4, so that the inner walls of the bearing-bars are substantially coincident with the inner 85 walls of the trough.

D is a hopper secured to the foot-plate or deck of the locomotive above the rear end of the trough C. The rear wall d of the hopper is hinged at its base to the foot-plate, so as to 90 be capable of folding backwardly and downwardly. Each of the side walls d' d' is similarly hinged at its base to the foot-plate, so as to be capable of folding outwardly and downwardly. Any fuel-supply device may 95 be substituted for the hopper.

Extending between and through the bearing-bars Y Y are a plurality of shafts e, having secured thereto, between the bearing-bars, deflectors E, extending normally down 100 into the trough C. Embracing and secured to the outer ends of said shafts, outside of the bearing-bars, are arms F, resting upon stops f, secured to the outside of the bearing-

bars. *g* represents lugs secured to the outside of the bearing-bars, and *G* represents springs, one end of each spring being secured to said arm *F* and the other end to said lug *g*. The 5 deflectors *E* are thus free to swing forwardly and upwardly, except so far as they are restrained by the springs *G*; but they are prevented from swinging backwardly beyond the vertical position by the engagement of arms 10 *F* against stops *f*.

Secured near the rear end of the trough and overhanging the same is a flat plate *K*, preferably toothed, as shown.

I have provided the following means for 15 reciprocating the trough *C*: Secured to a cross-tie *L* of the locomotive is a motor *H*. This motor consists of a cylinder and piston and valve-gear of any ordinary construction, the same being driven by steam from the boiler 20 or by compressed air from the brake system. The piston-rod *h* is attached to a lug *c'*.

The operation of the stoker constructed as I have described is as follows: Normally the parts are in the positions shown in Figs. 1 to 25 5, inclusive. The plate *K* is immediately back of the mouth of the hopper, and the deflectors *E* hang vertically, permitting coal to be deposited into the trough. Steam or air being admitted to the cylinder of motor *H*, the 30 trough or conveyer *C* reciprocates. The initial movement is a forward one, causing the coal to be carried forward, and the forwardly-moving plate crushes or breaks any large masses or lumps of coal that may be lodged 35 in the mouth of the hopper. The backward movement of the trough uncovers the mouth of the hopper and permits another charge of coal to be deposited into the trough. At each successive forward movement of the trough 40 40 the contained coal is carried forward and a fresh supply of coal is received from the hopper until the trough is filled throughout its entire length. The deflectors *E* are actuated in the following manner: In the forward 45 movement of the trough the forwardly-moving coal pushes the deflectors forwardly and upwardly on their pivots. (See Fig. 6.) On the return stroke the deflectors swing in the opposite direction—*i. e.*, downward and backward, (see Fig. 7)—being urged in that direction by the return movement of the coal and further constrained by the springs *G*. The 50 deflectors cannot swing back beyond a vertical position, as their movement is stopped by 55 the engagement of arms *F* with stops *f*.

By the described operation a portion of the coal contained in the trough is lifted and deposited on the grate-surface either in front of or behind the respective deflectors during 60 both the forward and backward movement of the trough.

The location and size of the deflectors will depend upon the particular design of the locomotive to which the stoker is applied and 65 will also depend upon the dimensions of the trough and the distance thereof below the grate-surface. Ordinarily, however, if the

deflectors are of uniform size and uniformly distributed beneath the grate-surface the tendency will be to distribute the coal un- 70 equally and discharge an excessive quantity of coal over the portion of the grate-surface farthest from the hopper. I find that I can obviate this by placing the deflectors of larger dimensions nearer the hopper end of the stoker. 75 Thus the deflector nearest to the hopper is shown as substantially longer than the deflector farthest from the hopper, while the intermediate deflector or deflectors is shown as of an intermediate length. Thus the tendency 80 to bank up the coal at the front of the grate is counteracted by the decreased feeding capacity of that end of the stoker. The deflector nearest the throat of the hopper besides acting as a fuel-distributer performs 85 also the specific purpose of a gate, as it prevents the coal on the return stroke from being drawn back under the mouth of the hopper, which would prevent a fresh charge of coal falling into the conveyer or trough. 90

Having now fully described my invention, what I claim, and desire to protect by Letters Patent, is—

1. In a mechanical stoker, the combination, with the grate, of a fuel-retort beneath the 95 grate, means for reciprocating the fuel-retort, fuel-distributing devices within the retort, and means to introduce fuel to the retort.

2. In a mechanical stoker, the combination, with the grate, of a conveyer beneath the 100 grate, means for reciprocating the conveyer, deflectors within the conveyer adapted to swing on stationary pivots, and means to introduce fuel to the conveyer.

3. In a mechanical stoker, the combination, 105 with the grate, of a fuel-retort beneath the grate, means for reciprocating the fuel-retort, fuel-distributing devices within the retort but not movable therewith, and means to introduce fuel to the retort. 110

4. A mechanical stoker consisting of a reciprocatory fuel-containing trough, and deflectors within the trough adapted to swing on stationary pivots.

5. In a mechanical stoker, the combination, 115 with the grate, of a fuel-retort beneath the grate, means for reciprocating the fuel-retort, movable fuel-distributing devices within the retort but not reciprocating therewith, and means to introduce fuel to the retort. 120

6. A mechanical stoker consisting of a reciprocatory fuel-containing trough, deflectors within the trough adapted to swing on stationary pivots, and a hopper at one end of the trough, the deflector nearest the hopper 125 being substantially larger than the deflector most remote from the hopper.

7. A mechanical stoker consisting of a reciprocatory fuel-containing trough, and deflectors within the trough adapted to swing 130 on stationary pivots, and a hopper at one end of the trough, the deflector nearest the hopper being substantially larger than the deflector most remote from the hopper, and the

intermediate deflector or deflectors being of intermediate size.

8. In a mechanical stoker, the combination, with the grate and the hopper, of a fuel-retort extending beneath the grate and the hopper, means for reciprocating the fuel-retort, and independent fuel-distributing devices within the retort.

9. In a mechanical stoker, the combination, with the grate, of a fuel-containing trough having floor and sides and open at the top and located beneath the grate, means for reciprocating the trough, means to introduce fuel into the trough at one end thereof, and a deflector or gate, within the trough, but not movable therewith, adjacent to that end of the grate nearest the fuel-supply end of the trough.

10. In a mechanical stoker, the combination, with the grate, of a conveyer beneath the grate, means for reciprocating the conveyer, means to introduce fuel into the conveyer at one end thereof, and a gate within the conveyer adjacent to that end of the grate nearest to the fuel-supply end of the conveyer, said gate being adapted to swing on a stationary pivot.

11. A mechanical stoker consisting of a reciprocatory fuel-containing trough, deflectors within the trough adapted to swing on stationary pivots, said deflectors occupying a normally vertical position, and tension devices tending to restore said deflectors to their normal or vertical position.

12. A mechanical stoker consisting of a reciprocatory fuel-containing trough, deflectors within the trough adapted to swing on stationary pivots, said deflectors occupying a normally vertical position, and stops adapted to limit the movement of said deflectors in one direction.

13. A mechanical stoker consisting of a reciprocatory fuel-containing trough, deflectors within the trough adapted to swing on stationary pivots, said deflectors occupying a normally vertical position, tension devices tending to restore said deflectors to their normal position, and stops adapted to limit the movement of said deflectors in one direction.

14. In a mechanical stoker, the combination, with the grate, of two bearing-bars, spaced apart, beneath the grate, a fuel-containing trough having floor and sides and open at the top and located beneath said bearing-bars, means for reciprocating the trough, fuel-distributing devices within the trough but not movable therewith, and means to introduce fuel to the trough.

15. In a mechanical stoker, the combination, with the grate, of two bearing-bars, spaced apart, beneath the grate, a fuel-containing trough having floor and sides and open at the top and located beneath said bearing-bars, the inner walls of the bearing-bars and the inner side walls of the trough being substantially coincident, means for reciprocating the trough, fuel-distributing devices within the

trough but not movable therewith, and means to introduce fuel to the trough.

16. A mechanical stoker consisting of two stationary bearing-bars, spaced apart, a fuel-containing trough having floor and sides and open at the top and located beneath said bearing-bars, means for reciprocating the trough, and fuel-distributing deflectors attached to said bearing-bars.

17. A mechanical stoker consisting of two stationary bearing-bars, spaced apart, brackets depending therefrom, rollers sustained in said brackets, a fuel-containing trough having floor and sides and open at the top and resting on said rollers, and means to reciprocate the trough.

18. A mechanical stoker consisting of two stationary bearing-bars, spaced apart, brackets depending therefrom, rollers sustained in said brackets, a fuel-containing trough having floor and sides and open at the top and resting on said rollers, fuel-distributing deflectors attached to said bearing-bars, and means to reciprocate the trough.

19. A mechanical stoker consisting of two stationary bearing-bars, spaced apart, a conveyer beneath said bearing-bars, means for reciprocating the conveyer, a shaft extending between said bearing-bars, said shaft carrying a fuel-distributing deflector within the conveyer and an arm outside thereof, and a stop adapted to engage said arm and thus limit the movement of said deflector in one direction.

20. A mechanical stoker consisting of two stationary bearing-bars, spaced apart, a conveyer beneath said bearing-bars, means for reciprocating the conveyer, a shaft extending between said bearing-bars, said shaft carrying a fuel-distributing deflector within the conveyer and an arm outside thereof, a stop adapted to engage said arm and thus limit the movement of said deflector in one direction, and a tension device secured to one of said bearing-bars and tending to swing said deflector in one direction.

21. A mechanical stoker consisting of two stationary bearing-bars, spaced apart, a conveyer beneath said bearing-bars, means for reciprocating the conveyer, a shaft extending between said bearing-bars, said shaft carrying a fuel-distributing deflector within the conveyer and an arm outside thereof, a stop adapted to engage said arm and thus limit the movement of said deflector in one direction, brackets depending from said bearing-bars, and rollers sustained in said brackets, said conveyer resting on said rollers.

In testimony of which invention I have hereunto set my hand, at Philadelphia, on this 27th day of May, 1902.

ELLICOTT McCONNELL.
